COIN CONTROLLED GAME APPARATUS

Moyce H. Sikes, Atlanta, Ga.

Application December 12, 1940, Serial No. 369,877

3 Claims. (Cl. 273—11)

This invention relates to coin controlled game apparatus and more particularly to a coin controlled pocket billiard or pool table or the like.

The primary object of this invention is the provision of an improved table of this character so arranged that a rack of balls may be made available to a player or players upon the introduction of a coin into the device, such balls being returned to such a position as to become again accessible to the players upon the introduction of an additional coin, as each is played.

A secondary object of this invention is the provision in such a table, of improved means whereby the balls scored by each player may be retained in separate compartments until a full rack has been played.

A further object is the provision of means whereby balls contained in such separate compartments are visible to the players during the course of the play and after completion of the play of a rack.

An additional object is the provision of improved means whereby scratched balls may be returned to the player without the necessity of inserting an additional coin.

A more specific object resides in the provision of improved means to control the number of scratched balls so returnable during the play of a single rack of balls.

Additional objects reside in the provision of such a device of durable, relatively simple construction having a comparative minimum of operating parts, thus reducing the hazard of operating failure and increasing reliability of operation.

Other objects will in part be obvious and in part pointed out hereinafter.

The invention accordingly resides in the combinations of elements, arrangements of parts and features of construction all as will be more fully described in the annexed specification and disclosed in the accompanying drawings, where-

Figure 1 is an isometric view of a pool or billiard table embodying one form of this inventive concept.

Figure 2 is a sectional view taken along the line 2—2 of Figure 3.

Figure 3 is a top plan view partially in section disclosing a table having the playing surface thereof removed and having certain portions of the interior mechanism constituting a part of this invention partially cut away.

Figure 4 is an enlarged sectional detail view taken along the line 4—4 of Figure 3.

Figure 5 is an enlarged sectional detail view taken along the line 5—5 of Figure 3.

Figure 6 is an enlarged detailed sectional view taken along the line 6—6 of Figure 3.

5 Figure 7 is a top plan fragmentary view, partially in section, disclosing a table having the playing surface thereof removed and having certain portions of the interior mechanism partially cut away disclosing a modified form of construction of certain details.

Figure 8 is a sectional view taken along the line 8—8 of Figure 7 as viewed from the left.

10 Figure 9 is a sectional view taken along the line 9—9 of Figure 7 as viewed from the bottom.

15 Figure 10 is a schematic plan view of certain portions of the operating mechanism of a modified form of construction.

Figure 11 is a view similar to Figure 10 showing a further modified form of construction, and

20 Figure 12 is a view similar to Figures 10 and 11 showing a still further modification of this inventive concept.

25 Similar reference characters refer to similar parts throughout the several views of the drawings.

Having particular reference now to Figure 1 there is generally indicated at 20 a pool or billiard table having a playing top 21, legs 22, and pockets 23 for the reception of played balls, with 30 which is associated one form of apparatus generally indicated at 24, embodying this inventive concept.

35 Pockets 23 communicate directly with a space beneath the table top 21, the bottom of which space is comprised of two angularly disposed surfaces 26 and 27 which incline oppositely towards a central trough or groove 28 running the full width of the table. Thus it will be seen that a ball entering any of pockets 23 falls therethrough and strikes either inclined surface 26 or 27 and rolls by gravity into trough 28. As is best shown in Figure 4, trough 28 is likewise inclined towards one side of the table. Accordingly, a ball 40 entering trough 28 rolls down the same into a box-like receptacle or compartment generally indicated at 29 secured in any suitable manner to one side of the table until it abuts a stop member or barrier 30 positioned adjacent the end of the trough at its point of egress from the table, but spaced therefrom a distance substantially equal to the width of a ball. Relatively low barriers 31 and 32 are provided adjacent stop member 30 to constitute therewith a detaining pocket to preclude lateral displacement of a ball 45 50 55

abutting stop member 30 except under circumstances to be hereinafter pointed out.

Receptacle 29 is provided with suitable end walls 33 and 34 and a front wall 35 which may be, if desired, of glass, or comprise an open grill work of glass or other transparent material, likewise with a top wall 36 also of glass, or grill work (see Figures 3, 4 and 5) which extends over only a portion of the top thereof. One edge of glass top wall 36 may be set in a bar 37 of wood or other desired material in order to secure the same in related assembly. A space generally indicated at 38 is thus left between bar 37 and the side of the table. Across this space extends a second bar 39 leaving openings 38a and 38b on either side thereof each of a width slightly less than the diameter of the playing ball. In the operation of the device a played ball abuts stop 30 and remains in abutting relation therewith until it is grasped by the fingers of a player, raised over barrier or guide member 31 or 32 and moved laterally with respect to bar 39, until it reaches a desired spot, whereupon it is released and allowed to roll by gravity over bottom 40 of compartment 29 towards the forward wall 35 thereof. Bar 39 also precludes removal of playing balls from space 38. It may here be pointed out that receptacle or compartment 29 is divided interiorly by means of partitions 41 (see Figure 3) into four separate receptacles or sub-compartments. Thus, each player, since in the normal use of such a table, not more than four play, may guide those balls which he has scored to one of the sub-compartments as above indicated, and upon releasing the same in the desired position, have the ball fall into his individual compartment.

Thus, upon the conclusion of the play of a rack of balls, all those played will be in the sub-compartments of compartment 29 and available for return to the players in a manner now to be pointed out.

The bottom of the forward portion of compartment 29 on which the played and sorted balls rest is comprised of a shelf 40a adapted to be moved in a manner to be hereinafter pointed out, by means of extending lever members 42, (see Figures 3 and 4) connected to links 43 as by pivots 44. The opposite ends of links 43 are suitably secured to a transversely extending rod 45 which extends slightly more than the full width of compartment 29. Thus, it will be seen that as rod 45 is rotated in a manner to be hereinafter described, shelf 40a is withdrawn permitting the balls in compartment 29 to drop into the space 46 below shelf 40a, (see Figures 4 and 5) and upon striking the inclined bottom 47 thereof to roll downwardly through an aperture 48 (see Figure 3), into a basket 49 or other suitable receptacle (see Figure 1).

Adjacent receptacle 29 is a suitable coin receiving mechanism 50, (see Figures 3 and 6) including a plunger member 51, a coin receiving receptacle 52 and a rearwardly extending projection 53 actuated by the inward pressure of plunger 50. Projection 53 is adapted to engage an arm 54 rigidly secured to rod 45 and move the same through an angle in this illustrative embodiment of approximately 60°, imparting rotational movement to rod 45 which, in the manner previously pointed out, moves shelf 40a to permit the balls to fall into basket 49. An additional arm 55 is also secured to rod 45 and is adapted to extend upwardly through a slot 56 in the bottom of trough 28 when plunger 51 is pushed in-

wardly, thus to preclude passage of balls from chute 28 into compartment 29 in order to prevent an individual from playing an unlimited number of games by the expedient of pushing the coin slot in and holding the same in its inserted position. It is to be understood that any suitable spring mechanism (not shown) returns rod 45 and hence shelf 40a to compartment closing position.

Suitable apparatus is also provided to permit the return of scratched balls, that is, balls inadvertently pocketed and not counting towards a player's score. This mechanism comprises an open receptacle or pocket 57 adjacent one end of compartment 29 into which a player may guide a scratched ball and from which the ball may be removed and replaced on the table. Mechanism is also provided, however, to limit the number of scratched balls recovered during the playing of any given rack. One form of such mechanism is disclosed in Figures 3 and 5 wherein there is shown a star wheel 58 rotatably mounted as by means of a pin 59. A peripheral portion of star wheel 58 extends through a slot 60 in the table wall into compartment 29. A guide member 61 is provided adjacent star wheel 58, and in order to pass a ball into return compartment 57, it must be passed between guide members 61 and star wheel 58. Each ball passing therethrough rotates one tooth of star wheel 58 in a clockwise direction. A pawl 62 pivoted as at 63 precludes counterclockwise rotation of star wheel 58 during the normal course of play. Star wheel 58 is provided peripherally with a plurality of holes into the end one of which may be inserted a pin 64 adapted at the start of a game to be positioned on the left hand side of a stop member 65. Thus, each time a ball is passed through the scratch mechanism, pin 64 moves in a clockwise direction with star wheel 58 until such time as it abuts the right hand side of stop 65, at which time further rotation of the star wheel is precluded until the pin is returned to its original position by insertion of an additional coin in a manner now to be described. If desired a second pin (not shown) may be inserted into an additional hole in the periphery of star wheel 58 and the distance which the same may be rotated limited by the distance between the pins to limit the number of balls returned through the scratch limiting mechanism.

Rod 45 is provided with a projection 66 adapted upon rotation of rod 45, in the manner previously described, to engage a projection 67 associated with pawl 62 to move the same out of engagement with the teeth of star wheel 58, whereupon star wheel 58 is rotated in a counterclockwise direction as by means of a spiral tension spring 68.

Upon return of rod 45 to its normal position, a coil spring 69 returns pawl 62 to its position of engagement with the teeth of star wheel 58.

Having reference now to Figures 7 to 9 inclusive there is disclosed a modified form of scratch ball return limiting mechanism. In the construction herein disclosed a portion of the table is generally indicated at 220 provided with an apparatus generally indicated at 224 comprising a portion of this inventive concept.

A trough 228 similar to trough 28 guides a ball into receptacle 229 until such time as it abuts a stop 230 and is held between guide members 231 similar to guides 31 and 32. The end and front walls of receptacle 229 are designated by the reference characters 234 and 235 respectively.

A transverse bar 237 holds the glass top wall 75 236 in position to partially cover receptacle 229.

A second bar 239 across an open space 238 precludes manual removal of played balls from the receptacle, but permits their lateral movement.

The bottom of receptacle 229 indicated at 240 and its movable shelf 240a are moved by a pair of levers, one 242 of which is shown in Figure 7. Lever 242 is pivoted to a link 243 as by means of a pivot 244. Link 243 is in turn fixedly associated with a rod 245 adapted to be rotated through an angle of approximately 60° in a manner and by a method similar to that previously discussed in connection with rod 45. Partitions 241 divide receptacle 229 into a plurality, preferably four, of sub-compartments.

A lever 255 adapted to pass through a slot 256 extends into trough 228 and precludes movement of the balls through the apparatus when rod 245 is rotated rearwardly by means of a coin controlled mechanism similar to that disclosed in Figures 3 and 6.

A scratched ball is adapted to be returned to an open receptacle 257 by passing it interiorly, with respect to the table, of a stop member 261 and mechanism is provided to limit the number of balls returned. This mechanism in this embodiment takes the form of a lever 265 pivoted as by a pivot 266 to permit lateral displacement thereof in a direction towards receptacle 257. A spring 267 normally biases lever 265 in a direction towards guide members 231 and 232.

A projecting member 268 is pivoted as by a bolt 269 to lever 265 in such manner as to permit vertical movement thereof. Member 268 extends into engagement with the teeth 270 of a rack member 271, which teeth form a ratchet permitting the movement of rack member 271 towards the right as viewed in Figures 7 and 9. A spring 272 normally biases rack member 271 towards the left. It will now be seen that as lever 265 is swung through an arc toward the left, extension 268 engages the rear surface of a tooth 270 and forces the same toward the right, simultaneously riding down inclined surface 273, into engagement with which its free end extends, into abutting relation with such surface. After the ball has passed spring 267 returns lever 265 to normal position, the free end of member 268 rides over teeth 270 and then up inclined surface 273 and is released from engagement with teeth 270 until such time as lever 265 is again swung towards the left by passage of a ball thereby. Means are provided for normally precluding the return movement of rack 271 toward the left, such means taking the form of an extending member 274 pivoted as by a bolt 275 to a fixed projection 276. Thus, it will be seen that after a ball is moved past lever 265, rack 271 is moved a distance equal to one or more teeth thereon toward the right and held in its new position by member 274.

A stop member 277 is provided, which precludes further travel of rack 271 towards the right after the passage of a certain number of balls. If desired, stop 277 may be made movable, whereby the number of scratched balls returned in a given rack may be governed.

Means are provided for raising extending member 274 out of engagement with the teeth 270 of rack 271 upon the insertion of a coin in the mechanism. As previously pointed out such coin insertion causes rotation of rod 245. Attached to rod 245 is an arm 278 having an extending finger 279 normally positioned adjacent to and under extending member 274. Thus, rotation of rod 245 causes the removal of extending member 274 from its engagement with rack 271 which rack

is then urged by spring 272 towards its full left hand position, it being understood that member 268 is held out of engagement therewith by inclined surface 273 except at such times as lever 265 is moved towards the left.

Suitable guides 280 are provided to define the path of movement of rack 271. A suitable cover member 281 indicated by dotted lines (see Fig. 7) is provided to preclude the manual movement of lever 265 to the left or the holding of the same in its left hand position to permit the return of an unlimited number of scratched balls.

From the foregoing, the operation of the device should now be readily understood. Playing balls contained in compartment 29 are released by the insertion of a coin in the coin mechanism 50 in the manner previously described and are dropped into basket 49. The players then rack the balls on the table and as each ball falls into a pocket it rolls in the manner previously described to a position where it may be touched, but not removed, by the player, adjacent stop member 39. The player may then either move the same to any of the four sub-compartments of compartment 29 where such ball remains until an additional coin is inserted, or he may return the same to be replayed by use of a scratch return mechanism as above described. Thus it will be seen that the necessity for an attendant is substantially eliminated and succeeding racks of balls may be played as successive coins are introduced.

Figures 10, 11 and 12 are schematic views disclosing three modified forms of this inventive concept. Each view represents a pool table having its playing surface and upper ball guiding inclined surfaces removed. In each case, two inclined surfaces similar to surfaces 26 and 27 guide played balls from the pockets to a substantially centrally disposed trough, which guides the balls to the mechanism for segregating the same.

Having specific reference now to Figure 10, there is generally indicated at 15 a pool table, at one end of which is a compartment 76 divided into four sub-compartments. A guide chute 77 is centrally disposed with respect to these compartments. Chute 77 may take the form in cross-section of an inverted U and is pivoted to one of the angularly disposed guide surfaces (not shown), as at 78. A stop pin 79 is positioned on a suitably inclined surface sloping towards compartment 76 serving as the floor of the chute 77, and a suitable spring, not shown, holds chute 77 in central position. Thus, a ball dropping through an aperture into the position shown by ball 80 rolls down the inclined surface forming the base of chute 77 until it abuts stop pin 79. Then, by means of an exteriorly projecting handle (not shown) chute 77 may be rotated about pivot 78 to direct ball 80 into any one of the four divisions of compartment 76. The scratch mechanism in this form of device takes the form of a second chute 81 similar to chute 77 and pivoted as at 82. When it is desired to return a scratched ball, chute 81 which is closed at one end 83, is rotated to the position shown in dotted lines by means of a suitable handle (not shown) whereupon ball 80 rolls into chute 81 and is stopped by end wall 83. The chute is then returned by means of the aforementioned handle to the full line position, whereupon ball 80 is permitted to roll down a second oppositely inclined surface along a path defined by guides 84 to a suitable aperture 85 at the opposite end of the table.

A suitable spring wheel mechanism, generally designated at 86 which may be generally similar

in operation to the mechanism previously described and shown in Figure 3 in the primary embodiment of this invention, is also provided to limit the number of scratched balls returned. Likewise, suitable coin controlled apparatus (not shown) may be provided to permit the release of played balls from compartment 76.

Having reference now to Figure 11, a still further modified form of the device is disclosed, wherein a false bottom 90 is provided with a plurality of guideways 91, 92, 93, 94, 95, 96, 97, 98, and 99, adapted to direct a ball 100 into one of the sub-compartments of a suitable receptacle 101. The ball is dropped to the false bottom 90 and strikes a vertically tiltable member 102 pivoted as at 103 and provided with exteriorly projecting handles 104. A suitable spring mechanism, not shown, normally inclines member 102 into the direction towards compartment 101. Baffles 105, 106 and 107, are provided and pivoted as at 108, 109 and 110 respectively, to permit a ball passing between guides 98 and 99 to be directed into any of the sub-compartments of receptacle 101. Exteriorly projecting handles, not shown, are provided for the control of these baffles.

Upon rotation of either of handles 104, tiltable member 102 may be inclined downwardly in a direction towards the opposite end of the table from compartment 101 in which case a ball is directed by guides 111 and 112 along an inclined surface to a suitable open aperture 113 at the opposite end of the table from compartment 101, from which it may be recovered by a player. Suitable mechanism for limiting the number of scratched balls so returned may be, and preferably is provided as is a coin controlled mechanism, for permitting the replay of balls in container 101.

In the modification shown in Figure 12 an inclined surface 120 is provided, which for a major portion of its length inclines downwardly towards a receptacle 121 divided into suitable sub-compartments. Guideways 122, 123, 124 and 125 lead to these sub-compartments respectively. Positioned above each guideway is a slide member 126, 127, 128 and 129 respectively, each provided with oppositely disposed exteriorly protruding handles 130, 131, 132 and 133 respectively. Each of slide members 126 to 129 inclusive is provided with a central solid closure portion 134, 135, 136 and 137 respectively, closing the passageway to all guide ways 122 to 125 inclusive. However, apertures, 139, 140, 141 and 142 respectively, of a size to permit the passage of a ball are provided on opposite sides of each of solid portions 134 to 137 inclusive. Thus it will be seen by moving either of handles 130, for example, in either direction, a ball is permitted to drop into trough 122 and be guided by gravity to the associated sub-compartment of receptacle 121. Similarly, movement of handle 133 will guide a ball into trough 124 and hence its associated compartment.

The scratch return mechanism in this case is comprised of a similar slide 143 provided with exteriorly projecting handles 144, a central solid portion 145 and apertures 146. Movement of handles 144 permits the ball which enters the

lower surface from a point substantially directly above slide 143 to drop into an additional trough 147 and be returned to the player through a suitable aperture 148 at the opposite end of table 120, it being noted that the table bottom on the right hand side of slide 143 inclines downwardly towards the right hand end of the table.

The operation of the above embodiment should be readily understood from the foregoing. Suitable scratch return limiting mechanism and coin controlled mechanism may also be provided.

It will now be seen that there are thus provided several modifications of this inventive concept, achieving all the objects of this invention and others including many advantages of great practical utility.

As many embodiments may be made of this inventive concept, and as many modifications may be made in the embodiments hereinbefore set forth and disclosed in the accompanying drawings, it is to be understood that all such matter set forth or shown is to be interpreted merely as illustrative and not in a limited sense.

I claim as my invention:

1. A device of the character described for use with game apparatus employing balls, the device comprising a receptacle having therein a detaining pocket to initially receive the balls and also having compartments to which balls are distributable from said detaining pocket, a barrier means relatively low with respect to the height of the pocket and diameter of said balls to stop the passage of said balls to said receptacle but allowing space for the lifting of the balls thereover for passage to the receptacle and distribution to one of said compartments, said barrier means defining said pocket, said receptacle being closed to unauthorized removal of balls but at a part thereof being open to an extent enabling access to and manual gripping of the balls, and means for the discharge of balls from said compartments to the exterior of the receptacle.

2. A device of the character described for use with game apparatus employing balls, the device comprising a receptacle having therein a detaining pocket to initially receive the balls and also having compartments to which balls are distributable from said detaining pocket, a barrier means relatively low with respect to the height of the pocket and diameter of said balls to stop the passage of said balls to said receptacle but allowing space for the lifting of the balls thereover for passage to the receptacle and distribution to one of said compartments, said barrier means defining said pocket, said receptacle being closed to unauthorized removal of balls but at a part thereof being open to an extent enabling access to and manual gripping of the balls, and shelf means at the bottom of said compartments displaceable for discharge of balls to the exterior of the receptacle.

3. A device according to claim 2 wherein said shelf means forms the bottom of said compartments, an operating rod, levers extending from said shelf means, and crank connections from the rod to the levers whereby the shelf is displaceable to discharge balls to the exterior of the receptacle.

MOYCE H. SIKES.
